UNITED STATES PATENT OFFICE.

ASHELEIGH S. MOSES, OF ST. LOUIS, MISSOURI, ASSIGNOR TO NATIONAL LEAD COMPANY, OF ST. LOUIS, MISSOURI, A CORPORATION OF NEW JERSEY.

MACHINE FOR PRINTING LABELS DIRECTLY ON BUCKETS.

1,247,563.

Specification of Letters Patent. Patented Nov. 20, 1917.

Application filed March 12, 1913. Serial No. 753,750.

To all whom it may concern:

Be it known that I, ASHELEIGH S. MOSES, a citizen of the United States, and residing at St. Louis, in the State of Missouri, have 5 invented certain new and useful Improvements in Machines for Printing Labels Directly on Buckets, of which the following is a specification.

This invention relates to multi-color 10 printing presses and more particularly to printing presses adapted to print in different colors on cylindrical articles such as buckets and the like.

One of the objects of this invention is to 15 construct a machine in which the article to be printed is supported on a platen or mandrel which rotates with printing cylinders arranged in spaced relation circumferentially around the platen or mandrel.

20 Another object is to construct a machine in which the article can be quickly placed into and removed out of position, and in which correct register of the colors is insured.

25 Another object is to provide novel inking mechanism which is simple in construction, capable of adjustment, accessible, and which will distribute and apply the ink uniformly.

Another object is to provide a machine 30 which is simple in its construction and operation, cheap to manufacture, and further objects will appear from the detail description taken in connection with the accompanying drawings, in which:

35 Figure 1 is a plan of a machine embodying this invention.

Fig. 2 is a front elevation,

Fig. 3 is a partial side elevation of one of 40 the printing cylinders and its ink supply means, the view being taken looking in the direction of the arrow 3 Fig. 1,

Fig. 4 is a section on the line 4—4 Fig. 1,

Fig. 5 is a section on the line 5—5 Fig. 1,

Fig. 6 is a detail section on the line 6—6

45 Fig. 2,

Fig. 7 is a section on the line 7—7 Fig. 3,

Fig. 8 is a partial section on the line 8

Fig. 3,

Fig. 9 is a section on the line 9—9 Figs. 2 50 and 6, and

Fig. 10 is a front elevation of a bucket.

In the machine embodying this invention the article to be printed, such as a bucket, is supported on a platen or mandrel.

55 Around this mandrel are arranged a number

of printing cylinders which are geared to and rotate with the mandrel. The machine is entirely automatic in its operation so that when the bucket is placed on the mandrel and the machine is started the printing cylinders will successively engage and print on the bucket, and after the completion of the printing operation the bucket is automatically discharged from the mandrel. In this particular construction the machine is 60 adapted for printing buckets of tapered construction, the invention can however be embodied in machines for printing plain cylindrical buckets.

Referring now to the accompanying drawings 70 10 designates a base plate for supporting the bearings, brackets, etc. A main drive shaft 11 is supported in bearings 12 and 13 on the base plate and projects beyond the same. A platen or mandrel 14 is 75 mounted upon and keyed to the projecting end of the shaft and this mandrel is of tapered construction as shown. A sleeve 15 surrounds the shaft 11 and this sleeve has keyed thereto a driving pulley 16. The main drive shaft 11 has also keyed thereto 80 a cam block 17. The driving pulley 16 and the drive shaft 11 are arranged to be connected by means of a clutch generally indicated at 18 and having a treadle operated 85 clutch shifting rod 19. This clutch may be of any suitable construction but is preferably of the single revolution type, that is, so constructed that the shaft will upon depression of the treadle make a single revolution and then come to a stop in a predetermined position. Clutches of this type are however well known commercial devices and a detail description is therefore unnecessary.

90 A pair of shafts 20 are mounted in brackets 21 and 22 adjustably mounted on the base plate by means of screws 23 passing through slots in the brackets and tapped into the base plate. Adjusting screws 24 mounted 95 in lugs 25 on the base plate and engaging the brackets are provided for adjusting the brackets and the shafts laterally on the base plate. Each of the shafts 20 is provided with a reduced portion 26 adapted to receive a printing cylinder 27 of segmental form which is clamped in position on the shaft by means of a nut 28. Each of these cylinders is provided with a printing surface 29 of rubber or other suitable mate- 100

rial and having printing characters thereon. The shafts 20 are driven from the main drive shaft 11 by means of gears 30 keyed to the shafts 20 and meshing with a gear 31 keyed to the shaft 11. Where the mandrel is of tapered construction the gears 30 and 31 are bevel gears. In order to brake the machine each of the shafts 20 is provided with a friction drum 32 engaged by a friction brake 33. The base plate supports a pair of heads 40 which overhang the printing cylinders. These heads support the inking mechanisms hereinafter described.

The inking mechanism will now be described and since the inking mechanisms for the two printing cylinders are identical only one will be described in detail. The printing head 40 is provided with a pair of side members 41 forming bearings for the inking rolls. A pair of composition inking rolls 42 are adjustably mounted in the side members and retained in position therein as follows: The shafts of these rolls are mounted in U shaped blocks 43 movable vertically on the side members and having cheeks or lugs 44 bearing against the side members as shown in Fig. 9. Each of these blocks has a dove tailed slot 45 engaged by the head of a screw 46 threaded into a lug 47 projecting from the side member and having the end thereon slotted so that it can be engaged by a screw driver or other suitable tool. By means of this construction the blocks 43 can be adjusted vertically on the side members to adjust just the rolls 42 toward and from the printing cylinders. The rolls and blocks are retained in position by means of latches 48 pivoted on screws 49 tapped into the lugs 47 and having lugs 50 thereon adapted to engage the ends of the shafts of the rolls 42. When the latches are thrown up out of latching position the inking rolls can be readily removed, while when these latches are in position as shown in Figs. 2 and 3 they retain the rolls in position and against removal at the same time permitting adjustment of the blocks 43 and the rolls carried thereby. The connection between the blocks and the screws 46 permits these blocks to be removed and replaced. The lug 50 when in position engages the side of the block 43 while the latch body engages the front of the block to retain it in position. After the latch is in position it may be clamped by its screw 49.

A pair of plates 51 are secured to the side members 41 by means of screws 52 and these plates support the shaft 53 of a brass distributing roll 54. The shaft 53 carries a cam head 55 sliding and rotating in a bearing bracket 56 and having a cam groove 57 engaged by the end of a pin 58 threaded into the bracket. The shafts 53 have each a pulley 59 driven by belts 60 from a pulley 61 keyed to the sleeve 15. Guide pulleys 62 are

also provided for the belts 60 to sustain them laterally. By means of this construction the shafts 53 are rotated and given an endwise movement while rotating, and in view of the fact that these shafts are driven from the continuously rotating sleeve 15, the distributing rolls 54 are continuously rotated and reciprocated laterally.

A composition ink-receiving roll 63 mounted in stirrups 64 on the side members 41 engages with the distributing roll 54. A brass supply roll 65 is mounted between side members 66 pivoted at 67 on a part 68 mounted on the head 40. The part 68 is formed and beveled as shown at 69 so as to form with the side members 66 and the roll 65 an ink fountain. The shaft 70 of the roll 65 is driven intermittently by an intermittent clutch comprising a cylindrical casing 71 secured to the shaft, a head 72^a mounted in and movable in the casing and attached to an arm 72, and balls or rolls 73 between the casing and head. The arm 72 is oscillated through a link 74 from a bell crank lever 75 loosely mounted on a shaft 76 supported in bearing lugs 77 on the head 40. By means of this construction oscillation of the bell crank lever 75 will cause an intermittent movement of the roll 65 in a clockwise direction. In order to regulate the space between the part 68 and the roll 65, so as to regulate the feed of the ink, the side members 66 are arranged for movement on their pivot 67, and these side members are adjusted by means of screws 78 extending loosely through the side members 66 and threaded into the head 40. The springs 79 hold the roll in adjusted position. A composition transfer roll 80 is removably mounted in the ends of arms 81 rigidly connected to the shaft 76. The bell crank lever 75 is yieldingly connected to the shaft 76 by means of a coil spring 82 on the shaft connected at one end to a collar 83 on the shaft and at its other end to a boss 84 on the bell crank lever. By means of this construction the shaft 76 will be actuated yieldingly in both directions. The bell crank levers 75 are operated through a cross head 85 mounted on a slide 86 moving in a guide-way 87 and having a cam roll 88 engaging a cam 89 keyed to the shaft 11. The cross head is returned by a spring 90.

During the upward movement of the cross head the transfer roll 80 will be thrown into contact with the receiving roll 63 and since this roll 63 is continuously driven by the roll 54 the ink will be taken off of the roll 80 and transferred to the roll 63. During the return movement of the cross head and when the parts are moving in the direction of the arrows Figs. 5 and 7 the transfer roll 80 will be thrown into engagement with the supply roll 65, and since the movement takes place through the spring 82 the engagement be-

tween the rolls 80 and 65 will be a yielding one. During the return or downward movement of the cross head the arm 72 and the clutch connection between this arm and the roll 65 will cause this roll to be moved in the direction of the arrow Fig. 7 to present the inked portion of the roll to the transfer roll 80. The transfer roll 80 moves into engagement with the supply roll 65 while the latter is rotating, and in view of the fact that the yielding connection between the bell crank 75 and the shaft 76 causes the rolls 80 and 65 to be in engagement for some time while the roll 65 is still moving in the direction of the arrow Fig. 7, the ink will be transferred from the roll 65 to the roll 80.

The mandrel is recessed as shown at 91 to receive a plate 92 mounted on an endwise movable shaft 93 which has a head 94 on the end thereof. A spring 95 on the shaft 93 between the head 94 and the shaft 11 normally tends to throw the plate 91 to retracted position in the recess 91. A two armed lever pivoted at 96 on the base plate 10 has one arm 97 thereof bearing against the head 94 and the other arm 98 is provided with a cam roll 99 working in a cam groove 100 in the cam head 17. The plate 92 has an aperture 101 therein to permit escape of the air. The mandrel is provided with a notched positioning finger 102 adapted to engage the bail holder 103 of the bucket 104. The purpose of this finger is to position the bucket on the mandrel and retain it against rotation thereon.

Fig. 10 shows a printed bucket. The letters have a body of one color and a border of another color. In the operation of the machine, as hereinafter described, the body of these letters will be printed by one printing cylinder while the border will be printed by the other printing cylinder.

The operation of the machine is as follows: The ink fountains are supplied with different colored inks so as to print in different colors on the bucket. Prior to placing a bucket on the mandrel the machine is run several revolutions so as to thoroughly ink the inking rolls as well as to transfer the ink to the type on the printing cylinders.

As the parts move in the directions of the arrows Fig. 2, and as the printing cylinders pass under the inking rolls 42, the ink will be applied to the type on each cylinder. These inking rolls 42 are supplied with ink as heretofore described. A bucket is now placed on the mandrel and positioned thereon by the positioning finger 102. If the machine is now started by depression of the treadle the drive shaft will make one revolution and come to a stop. During this single revolution of the drive shaft the left printing cylinder will first engage and print on the bucket, (to form for instance, the body of the letters) and thereafter the right

hand printing cylinder will engage and print on the bucket (to form for instance, the border of the letters). It will be noted that the printing cylinders are so arranged with respect to the mandrel that they are spaced in time relation 180° or a half of a revolution so that one will follow the other. After a complete revolution the ejector plate 92 will be thrown out to discharge the bucket from the mandrel. This ejector plate will be operated near the end of the revolution so that it will be thrown out and withdrawn again when the machine comes to a stop, whereby the machine when stopped will be in condition to receive another bucket. During this revolution of the machine the type have been inked, and the supply, transfer and the distributing rolls have been operated to supply ink to the inking rolls 42. While the bucket is in position on the mandrel and while it is engaged by the printing cylinders it is retained thereon by the cylinders, due to the tapered construction of the mandrel. No auxiliary holding means is therefore necessary to hold the bucket on the mandrel in this tapered construction. The segmental construction of the printing cylinders permits removal of the bucket when these cylinders are out of printing position.

It will therefore be seen that the machine is entirely automatic in its operation. The arrangement of the printing cylinders circumferentially around the mandrel and the gear connections between these parts results in an accurate operation of the machine. The printing cylinders can be accurately adjusted on their shafts, one with respect to the other to cause an accurate register of the colors. The arrangement of the printing cylinders around the mandrel permits a design of a series of colors to be printed on a cylindrical article without complication of the mechanisms. While only two printing cylinders have been shown it will be seen that their number may be varied.

It is obvious that various changes may be made in the details of construction without departing from the spirit of this invention and it is therefore to be understood that this invention is not to be limited to the specific construction shown and described.

Having thus described the invention what is claimed is:

1. A machine for printing labels directly on buckets, comprising a frame, a mandrel supported for rotation on said frame and constructed and arranged to receive and hold a bucket placed endwise thereover and for rotation therewith, a printing cylinder mounted for rotation on said frame and having a printing surface adapted to engage and print directly on the curved surface of the bucket on said mandrel, and mechanism positively connecting said man-

drel and said bucket thereon with said cylinder, adapted to positively cause and insure the engaging surfaces of the bucket and said cylinder to move at the same surface speed, 5 said mechanism being adapted to drive said mandrel and said cylinder in timed relation, substantially as and for the purpose set forth.

2. A machine for printing labels directly 10 on buckets, comprising a frame, a tapered mandrel supported for rotation on said frame and constructed and arranged to receive and hold a tapered bucket placed endwise thereover and for rotation therewith, a 15 tapered printing cylinder mounted for rotation on said frame and having a printing surface adapted to engage and print directly on the tapered and curved surface of the bucket on said mandrel, and mechanism 20 positively connecting said mandrel and said bucket thereon with said cylinder, adapted to positively cause and insure the engaging surfaces of the bucket and said cylinder to move at the same surface speed, said mechanism 25 being adapted to drive said mandrel and said cylinder in timed relation, substantially as and for the purpose set forth.

3. A machine for printing labels directly 30 on buckets, comprising a frame, a mandrel supported for rotation on said frame and constructed and arranged to receive and hold a bucket placed endwise thereover and for rotation therewith, a plurality of printing cylinders mounted for rotation on said frame and arranged in spaced relation circumferentially around said mandrel, said cylinders bearing printing surfaces corresponding respectively to the component parts of the label to be printed, and mechanism 40 connecting said mandrel and said bucket thereon with said cylinders, adapted to positively cause and insure the engaging surfaces of the bucket and said cylinders to move at the same surface speed, and constructed and arranged to cause said printing 45 surfaces to print successively their respective portions of the label in registered relation directly on the curved surface of the bucket, said mechanism being adapted to 50 drive said mandrel and said cylinders for operation in timed relation, substantially as and for the purpose set forth.

4. A machine for printing labels directly 55 on buckets, comprising a frame, a tapered mandrel supported for rotation on said frame and constructed and arranged to receive and hold a tapered bucket placed endwise thereover and for rotation therewith, a plurality of tapered printing cylinders 60 mounted for rotation on said frame and bearing printing surfaces bearing respectively component parts of the label to be printed, and mechanism connecting said mandrel and said bucket thereon with said cylinders, adapted to positively cause and in-

sure the engaging surfaces of the bucket and said cylinders to move at the same surface speed, and constructed and arranged to cause said printing surfaces to print successively their respective portions of the label 70 in registered relation directly on the tapered and curved surface of the bucket, said mechanism being adapted to drive said mandrel and said cylinders in timed relation, substantially as and for the purpose set forth. 75

5. In a printing press, the combination with a rotary mandrel formed to fit within and support a bucket, of a plurality of printing members mounted adjacent said mandrel in position to print successively and 80 in registered relation on the bucket during a single revolution of the latter, means on the mandrel for engaging a part of the bucket and positively holding the latter in a predetermined position on the mandrel, said means comprising a forked member for engaging the bail-holder of the bucket, whereby said printing members will be caused to print upon the bucket in a definite predetermined relation to its bail, and means for rotating said mandrel and operating said printing members. 85

6. In a machine for printing on buckets, the combination with a rotary platen adapted to receive and support a bucket, of a plurality of printing cylinders mounted in spaced relation circumferentially around said platen and arranged to print successively and in registered relation on the bucket during a single revolution of the latter, means interconnecting said cylinders and platen to move together, and means acting automatically at the end of one revolution of the platen to stop said cylinders and platen. 95

7. In a machine for printing on buckets, the combination with a rotary mandrel adapted to receive and support a bucket, of a plurality of printing cylinders mounted in spaced relation circumferentially around said mandrel and arranged to print successively and in registered relation on the bucket during a single revolution of the mandrel, means interconnecting said cylinders and mandrel to move together, and means acting automatically at the end of one revolution of the mandrel to eject the bucket therefrom. 110

8. In a machine for printing on buckets, the combination with a rotary mandrel adapted to receive and support a bucket, of a plurality of printing cylinders mounted in spaced relation circumferentially around said mandrel and arranged to print successively and in registered relation on the 120 bucket during a single revolution of the mandrel, means interconnecting said cylinders and mandrel to move together, means acting automatically at the end of one revolution of the mandrel to stop said cylinders. 125

and mandrel, and means operating immediately prior to the action of said stop means to eject the bucket from the mandrel.

9. In a machine for printing on buckets, the combination with a rotary mandrel adapted to receive and support a bucket, of a plurality of printing cylinders mounted in spaced relation circumferentially around said mandrel and arranged to print successively and in registered relation on the bucket during a single revolution of the mandrel, means interconnecting said cylinders and mandrel to move together, means operating to eject the bucket at the end of the printing operation, means acting automatically to stop said cylinders and mandrel at the end of one revolution of the mandrel, and means operating automatically after each ejecting operation to return the ejecting means to initial position.

10. In a machine for printing on buckets, the combination with a rotary mandrel adapted to receive axially thereover a bucket and support the same, of mechanism adapted to print on the bucket, inking mechanism for said printing mechanism, intermittently operable means for actuating said printing mechanism to print upon the bucket, and means actuated constantly and independently of said intermittent means for operating said inking mechanism.

11. In a machine for printing on buckets, the combination with a rotary mandrel adapted to receive and support a bucket, of mechanism adapted to print on the bucket, inking mechanism for said printing mechanism, a driver arranged to drive said inking mechanism constantly and independently of said printing mechanism, and means for intermittently connecting said mandrel and printing mechanism with said driver to effect the printing operation.

12. In a printing press, the combination with a rotary mandrel adapted to receive and support a bucket, of printing mechanism adapted to print on the bucket, inking mechanism for said printing mechanism, ejecting mechanism for said bucket, a driver connected to constantly drive said inking mechanism, and means for intermittently connecting said mandrel, printing mechanism and said ejector with said driver.

13. In a printing press, the combination with a rotary mandrel adapted to receive and

support a bucket, of printing mechanism driven from said mandrel and adapted to print on the bucket, an ejector on said mandrel, a continuously rotating driver, and means for intermittently connecting said mandrel, and said ejector with said driver. 60

14. In a printing press, the combination with a rotary mandrel adapted to receive and support a bucket, of printing mechanism driven from said mandrel and adapted to print on the bucket, an ejector mounted 65 axially of said mandrel, means for driving said mandrel, and means connecting said driving means with said ejector for operating the latter to remove the bucket at the end of the printing operation.

15. In a printing press, the combination with a rotary mandrel adapted to receive and support a bucket, of printing mechanism driven from said mandrel and adapted to print on the bucket, an ejector mounted 75 axially of said mandrel, a drive shaft for said mandrel, and means for operating said ejector from said drive shaft.

16. In a printing press, the combination with a rotary mandrel adapted to receive 80 and support a bucket, of mechanism adapted to print on the bucket, an ejector movable to engage and remove the bucket from the mandrel, a continuously rotating driving member, and manually controlled means for 85 transmitting motion from said member to said mandrel and printing mechanism and operating said ejector once for each revolution of the mandrel.

17. In a printing press, the combination 90 with a rotary mandrel adapted to receive axially thereover a bucket and support the same, the outer face of said mandrel being provided with a shallow recess, of an ejector plate adapted to fit in said recess in position 95 to engage the bottom of the bucket and provided with an air escape opening, printing mechanism and means for operating the same to print on the bucket, and means for actuating said ejector plate outwardly to remove the bucket at the end of the printing operation. 100

In testimony whereof I affix my signature in the presence of two witnesses.

ASHELEIGH S. MOSES.
